HEATER

Mark A. Replogle, Akron, Ohio, assignor to The
Replogle Heater Company, Akron, Ohio, a cor-
poration of Ohio

Application September 7, 1928, Serial No. 304,594

26 Claims. (Cl. 126—99)

This invention relates to heaters for domestic or industrial uses.

The general purpose of the invention is to provide a heater adapted to secure as nearly perfect combustion of coal as is possible to attain effective, economical heating without smoke, and this application is a continuation-in-part of prior applications Serial No. 49,763, filed August 12, 1925, and Serial No. 107,692, filed May 8, 1926.

Heretofore, there have been numerous attempts to provide a heater to attain the foregoing purpose, but substantially perfect and smokeless combustion has not been produced, although some considerable improvements in the efficiency of coal burners has, of course, been secured.

In order to obtain substantially complete combustion of coal, it is necessary to produce such temperatures and to so agitate and loosen the coking coals in a gassing pot that all of the gases, both those ignitable at the temperatures in the gassing pot and those ignitable at higher temperatures, the heavy as well as the light, shall be liberated from the coal. It is also necessary to provide the right quantity of air to burn a given amount of coal. And it is, furthermore, necessary to build up a reservoir of heat so that all the gases, including those ignitable at the higher temperatures, will burn. This requires production of a temperature in the neighborhood of 2,500° to 3,000° F. at some point in the heater where the last-named gases and free air may burn.

In all heaters heretofore employed, it has been impossible to so conserve the heat as to produce any such temperature because in all prior forms of heaters the radiation from the burning coals or gases has been so great as to prevent any such temperatures being reached.

The chief objects of the present invention, therefore, are to provide means for producing a self-perpetuating fire to which coal and air are supplied in the proper proportion to produce complete combustion at any determinate rate, to provide means for feeding the coals through the gassing pot at said rate and for keeping the coking coals thoroughly loosened so as to liberate all the gases, and to provide means for so conserving the heat of the liberated gases as to build up a reservoir of heat, causing ignition of those gases igniting at higher temperatures before they are delivered to the radiator.

A further object of the invention is to provide means in the gassing pot for preventing the accumulation of clinkers therein.

The foregoing and other objects are attained by the heater shown in the accompanying draw-

ings and described below. It is to be understood that the invention is not limited to the specific form thereof shown and described.

Of the accompanying drawings,

Figure 1 is a longitudinal section through the center of a domestic hot air heater embodying the invention;

Figure 2 is a front elevation thereof;

Figure 3 is a section on line 3—3 of Figure 1;

Figure 4 is a section on line 4—4 of Figure 1;

Figure 5 is a section on line 5—5 of Figure 1;

Figure 6 is an enlarged side elevation of the heater operating mechanism;

Figure 6^a is a detail view illustrating the pawl and ratchet which operates the secondary rotary drum; and

Figure 7 is an enlarged side elevation of the flue and dust box construction.

Referring to the drawings, the numeral 10 designates the outer casing of a domestic heater embodying the invention and the numeral 11 designates the inner casing or radiator, the air to be heated being supplied to the outer casing about the inner casing by means of an inlet duct 10^a and being delivered from the heater by the ducts 12, 12 leading to the various rooms in a building. It is to be understood that the invention is not limited to use in air heating systems and that other fluid heating medium may be circulated about the radiator.

The radiator casing 11 extends through the heater from the front to the back end thereof and has arranged in the lower portion thereof at the front end a gassing pot 13 beneath which is an ash pit 14. A door 15 gives access to the upper part of the radiator at the front of the heater and a door 16 gives access to the radiator at the rear of the heater. A door 17 gives access to the gassing pot and a removable cover plate 18 clamped onto an opening in the front of the ash pit to render the latter air tight, gives access to the ash pit.

To supply coal to the gassing pot 13, a hopper 19 is arranged at one side of the heater to receive slack or crushed coal or coal screenings and a conveyor 20 operating through the bottom of hopper 19 and extending through the outer casing 10 and radiator casing 11 is arranged to feed coal into the gassing pot delivering the same at an outlet 21 adjacent the top of the gassing pot. An agitator 19^a is arranged to be rotated in the hopper over the conveyor 20 so as effectively to keep the coal flowing into the conveyor.

The supply of air to the gassing pot is preferably maintained by the use of a positive blower

22 connected by a conduit 23 to a duct 24 extended through the outer and radiator casings beneath and adjacent to the coal conveyor and having an outlet 25 therefrom for delivering the 5 air to the ash pit 14. The coal conveyor and air duct are preferably provided in a unit construction mounted on a frame 26 between the gassing pot and ash pit, this frame sloping downwardly adjacent each side wall of the gassing pot forwardly of the coal and air ducts as indicated at 26^a and then extending horizontally as indicated at 26^b to the front of the heater. The arrangement of the air duct under the coal conveyor duct provides for keeping the coal cool and 10 preventing coking thereof in the conveyor. 15

A coal feeding and agitating drum 27 is journaled in the gassing pot beneath the coal outlet 21 to receive the coal thereon, this drum being of greater diameter at its center than at its sides, 20 i. e. of generally convex outer peripheral formation so that the swelling of the coking coals will tend to break them apart rather than to weld them together and so clinker up and bind the drum. The drum 27 is grooved as shown or otherwise 25 irregularly formed so as both to engage the coals and feed them through the gassing pot and to agitate the coals, keeping them loose to freely liberate their gases. The drum 27 is preferably made of carborundum, this highly refractory material being found necessary to resist the temperatures 30 obtained in the gassing pot. Due to the drum being of lesser diameter at the side, the stream of fuel is moved more slowly and tends to solidify more than at the central region of the drum. This prevents the air passing from 35 the bottom of the pot seeking paths of least resistance about the sides of the fuel stream and thus more equally distributes the air throughout the fuel stream.

40 In front of and spaced from drum 27 and arranged adjacent the front wall of the heater is an auxiliary agitator drum 28 of somewhat smaller diameter, the drums providing a path therebetween for the coking coals as they travel 45 slowly through the gassing pot. The drum 28 is also preferably carborundum.

A grate 29 is supported on frame 26 beneath the 50 agitators, the grate bars extending from adjacent the front of the heater to a point under and, in the specific form of heater shown, slightly beyond the center of the feeding and agitating drum 27.

The spaces about the main and auxiliary drums and between the grate bars provide access of air 55 from the ash pit to the gassing pot. In addition, air outlets 30, 30 are provided along the inclined portions of frame 26 on each side of the main drum 27.

It will be observed that the gassing pot construction provides for moving a stream of coal 60 forwardly, downwardly and then rearwardly, whereby the stream is inverted in passing through the pot over the grate.

The side walls of the gassing pot are lined 65 with fire clay as indicated at 31. The front wall 32 thereof is constructed as a removable section accessible through door 17 and in addition has a removable plug 33 therein. This wall is lined with carborundum blocks 34, this more highly refractory material being necessary because experience 70 has disclosed that the temperatures developed in the gassing pot fused fire clay and caused it to clinker up by adhesion of coking coal particles thereto.

To provide means for producing a reservoir of 75 heat such as necessary to burn the coal gases of

high ignition points which are liberated in the gassing pot, a refractory core 35 is provided in the radiator, the core preferably being constructed of sections which may be cemented together by a ceramic cement held in grooves 36, 36 and also secured together by bolts 37, 37. The front end of the core is supported on the gassing pot over an opening 38 in the top thereof and provides a dome 39 for the gassing pot, this dome being lined with highly refractory material such as carborundum blocks, the walls of the dome diverging downwardly (Figure 3) to prevent accumulation of ash or dust particles thereon. The rear end of the core is supported on the bottom of the radiator. The core as a whole or in sections may be removed through the rear radiator door. 80 85 90

An outlet, preferably restricted in size as compared with the area of the dome, is provided at 40 from the dome 39 for delivering the gases to a duct 41 extending back through the core 35 downwardly to the rear thereof and then upwardly to discharge outlet slots 42, 42 through the opposite sides of the core. The duct 41 defines a secondary or super-combustion chamber which, because of the concentration of heat adjacent the 100 restricted outlet 40, is partially lined with the highly refractory carborundum blocks 43, 43. The top surface of duct 41 is serrated or otherwise formed to provide baffles serving to thoroughly mix the combustible gases and air therein. 105

It will be observed that the core construction is such that the stream of gases follows a tortuous path in passing therethrough. This assists in effecting the building up of the heat reservoir in the core and aids in a thorough mixing of the 110 combustible gases with the oxygen content entering the core.

A removable plug 43^a is provided in the front of the core to which access is had through door 15 and a removable plug is provided at 44 at the rear and bottom of the core to which access is had through door 15, whereby the duct 41 can be easily cleaned out. An outlet 45 is provided in the bottom of the core at the rear for removal of the dust or ash cleaned from the duct, and a hinged plate 46 is arranged normally to close this outlet. 115 120 125

The main flue outlet from the radiator is provided at 47 in the bottom of the radiator at the center thereof just in back of the gassing pot, this outlet being connected by a flue duct 48 to a dust box 49 to one side of which the flue pipe 50 is connected. An upwardly swinging door 51 is provided at the rear of the dust box to give access thereto and a link 52 so connects this door with hinged plate 46 as to swing the latter open when the dust box door is opened. 130

It will be observed that there is a continuous natural suction on the radiator. The flue is constructed of such dimensions as to maintain a suction of such strength as always to maintain the pressure in the gassing pot and radiator substantially less than atmospheric. This prevents the leakage of gases from the gassing pot or 140 radiator into the home and renders it unnecessary to adopt expensive expedients for preventing gas leakage.

In order to permit starting of a fire without smoke backing up into the cellar, an auxiliary flue connection is provided to the top of the radiator at 53. This connection has a damper 54 therein operable from the front of the heater by a shaft 55 on which is a suitable wheel or crank 56. This damper is closed as soon as the flue 145 150

or chimney is heated sufficiently to draw the cold air from the radiator at the start.

The mechanism for operating the various parts of the heater in synchronism at any determinate rate for regulating the temperature in the house, includes a motor 57 slidably mounted on a base 57^a and shiftable thereon by a lever 58 which may be manually or thermostatically controlled as by connection of a cable 59 thereto which leads to a regulator (not shown) on an upper floor.

The motor 57 has thereon a friction disc 60 for driving a friction wheel 61, the disc 60 being movable to engage wheel 61 from its center to its periphery or vice versa by shifting of motor 57, whereby wheel 61 may be driven at any desired or regulated speed.

Wheel 61 is secured on a shaft 62 which directly drives blower 22. A sprocket 63 on said shaft drives a chain 64 which in turn drives a sprocket 65 secured on a shaft 66 for driving the coal feeding conveyor 20. This drive may be effected through suitable worm gearing in housing 67. The speed of conveyor 20 accordingly is synchronized with the speed of the blower and travels a slower rate, due to the speed reduction drive shown between the two, such that the coal and air are fed in definite proportions at any rate to which the heater is regulated, insuring complete combustion at all rates.

An eccentric 68 is mounted on the shaft of conveyor 20 which has a pin and slot connection with a crank 69 pivoted at 70 on housing 67, whereby the latter is oscillated. A pawl 71 is secured on said crank to engage with a ratchet wheel 72 on the shaft of the agitator 19^a in the hopper to actuate the same. A pawl 72^a is journaled on the eccentric 68 and engages with a ratchet wheel 73 secured on the main agitator 27 of the gassing pot for rotating the same intermittently in a clockwise direction (Figure 1), such intermittent rotation being preferred to continuous rotation thereof because the intermittent movement of this drum tends to break up the coking coals. A pawl 74 is carried by pawl 72^a to engage ratchet wheel 75 on the shaft of the auxiliary agitator 28 in the gassing pot to rotate said agitator in a counter-clockwise direction (Figure 1). It is to be noted that the three pawls 71, 72^a and 74 effect operation of the respective agitators over different portions of the cycle of rotation of the conveyor 20 so that the loads are effectively distributed over the whole cycle. The feeding action of the agitators 27 and 28, therefore, is at such a rate as compared with the coal and air feeds that the conveying of the coking coals through the fire and the delivery of the ash therefrom is maintained in proportion to the rate of combustion.

To start the operation of the heater, damper 54 is opened and a small fire is started in the gassing pot in the usual way as by use of paper, kindling and coal, the fire being built through the front gassing pot opening at 33. The cover plate 18 from the ash pit opening is removed (if it is desired) to permit natural draft through the grate. When a fairly good fire is thus produced, the cover plate 18 is replaced and the motor 57 is started, it being positioned for slow speed driving of the heater.

After operation in this manner for sufficient time to warm the flue 50, damper 54 is closed and the motor 56 is set to drive the heater at any determinate or regulated rate to produce the desired temperature in the house. Thereafter the fire is self-perpetuating.

The agitator 27, turning clockwise (Figure 1), gradually feeds the coking coals along a path forwardly and downwardly and then rearwardly and delivers the ash to the ash pit, the coals being thoroughly broken up due to its convex shape, the grooved formations on its surface and the intermittent movement thereof. The air is positively forced up about the drum 27 through the grate and through the apertures 30 along the side walls of the heater, the supply of air being in nowise affected by temporary clogging of openings with ash because the blower builds up the pressure when this occurs and forces the air through. This causes the coal stream to burn on both sides, on top and on the bottom, and prevents accumulation of fused ash on the side walls while at the same time the free air cools the side walls and gradually is brought up to the temperature for combustion of the gases liberated.

The inclined front wall 32 of the gassing pot tends to impell downwardly any ribbon of coking coals which may tend to bridge over from the agitator 27, and agitator 28, turning counter-clockwise (Figure 1), breaks up such coals and feeds them down between agitators 27 and 28. Air from the ash pit finds its way about the outside of the agitator 28 and up along the front wall of the gassing pot, causing the front of the coal stream to burn, cooling and preventing accumulation of fused ash on the front wall of the gassing pot and also becoming preheated for combustion of the gases, in the core above.

As the gases of combustion, the unburned gases and preheated air pass from the gassing pot through the core into the radiator, they gradually raise the dome of the gassing pot and the core, which absorbs the heat, to a high degree of temperature which is most highly concentrated at and adjacent the constricted outlet 40. This causes the gases ignitable at higher temperatures to burn. A temperature sufficient to cause ignition of the heavier gases in the core is maintained by reason of its great ability to absorb and retain heat and also by reason of the fact that the gases of combustion delivered from the core are forced to pass downwardly about the core to the flue outlet 47, maintaining a low temperature gradient through the wall of the core and insulating the core from the direct cooling effect of the radiating surfaces. The core becomes first red and then white hot on its inside.

The heater, in from three to four hours, accordingly reaches a condition in which all the gases are liberated from the coals in the gassing pot, those ignitable at lower temperatures being consumed therein and those ignitable at higher temperatures passing along with preheated air to the core which provides a reservoir of heat maintaining temperatures up to in the neighborhood of 2,500° to 3,000° F. and causing ignition and complete combustion of the heavier gases, the core passage being sufficiently long to give the required time for complete combustion of the gases before emptying into the radiator.

Though the apparatus is continuously supplying fresh coal to the gassing pot, there is a complete absence of smoke in the flue, the temperature in the core being such as to render impossible the emission of smoke therefrom.

It will be apparent from the foregoing that applicant has provided an efficient and smokeless coal heater requiring a minimum of attention, one which need only be started once each season and will operate continuously without other attention than the filling of the coal sup-

ply hopper and removing the ash occasionally, and cleaning after each season's operation.

The heater is controllable to provide any required quantity of heat between settings for maximum and minimum rate of fuel consumption and is easily regulated to deliver the amount of heat desired, the heater operating to produce complete combustion of the coal at all settings.

Modifications of the invention may be resorted to without departing from the spirit thereof or the scope of the appended claims.

What is claimed is:—

1. A heater construction comprising a gassing pot, means for continuously feeding solid fuel into the pot, a feeding and agitating drum in the pot for advancing the fuel through the pot while it is being consumed and for conducting the ash from the pot, said drum having a central raised peripheral portion, means for supplying air to the bottom of the pot for combustion purposes, a supercombustion chamber, there being a restricted opening connecting the pot and said chamber, said supercombustion chamber having a tortuous passageway with baffles therein, said gassing pot delivering hot air to the supercombustion chamber along with the gases liberated in the gassing pot, a radiator surrounding the supercombustion chamber, said supercombustion chamber emptying into said radiator adjacent to the top thereof through one or more restricted outlets, a flue connected to the bottom of the radiator, means for conducting a fluid to be heated about the radiator, power means for operating the feeding means, the drum and the air supplying means, and a single means for regulating the operation of the feeding means, the drum and the air supplying means to vary the rate of fuel consumption and the rate of supplying air to regulate the temperature of the fluid circulated about the radiator.

2. A heater construction comprising a gassing pot, means for continuously feeding solid fuel into the pot, a feeding and agitating drum in the pot for advancing the fuel through the pot while it is being consumed and for conducting the ash from the pot, said drum having a central raised peripheral portion, means for supplying air to the bottom of the pot for combustion purposes, a supercombustion chamber, there being a restricted opening connecting the pot and said chamber, said supercombustion chamber having a tortuous passageway with baffles therein, a radiator surrounding the supercombustion chamber, said supercombustion chamber emptying into said radiator adjacent to the top thereof through one or more restricted outlets, a flue connected to the bottom of the radiator, means for conducting fluid to be heated about the radiator, power means for operating the feeding means, the drum and the air supplying means, and a single means for regulating the operation of the feeding means, the drum and the air supplying means to vary the rate of fuel consumption and the rate of supplying air to regulate the temperature of the fluid circulated about the radiator.

3. A heater construction comprising a gassing pot, means for continuously feeding solid fuel into the pot, a feeding and agitating drum in the pot for advancing the fuel through the pot while it is being consumed and for conducting the ash from the pot, means for supplying air to the bottom of the pot for combustion purposes, a supercombustion chamber, there being a restricted opening connecting the pot and said

chamber, said supercombustion chamber having a tortuous passageway with baffles therein, said gassing pot delivering hot air to the supercombustion chamber along with the gases liberated in the gassing pot, a radiator surrounding the supercombustion chamber, said supercombustion chamber emptying into said radiator adjacent to the top thereof through one or more restricted outlets, a flue connected to the bottom of the radiator, means for conducting fluid to be heated about the radiator, power means for operating the feeding means, the drum and the air supplying means, and a single means for regulating the operation of the feeding means, the drum and the air supplying means to vary the rate of fuel consumption and the rate of supplying air to regulate the temperature of the fluid circulated about the radiator.

4. A heater construction comprising a gassing pot, means for continuously feeding solid fuel into the pot, a feeding and agitating drum in the pot for advancing the fuel through the pot while it is being consumed and for conducting the ash from the pot, means for supplying air to the bottom of the pot for combustion purposes, a supercombustion chamber, there being a restricted opening connecting the pot and said chamber, said supercombustion chamber having a tortuous passageway with baffles therein, a radiator surrounding the supercombustion chamber, said supercombustion chamber emptying into said radiator adjacent to the top thereof through one or more restricted outlets, a flue connected to the bottom of the radiator, means for conducting fluid to be heated about the radiator, power means for operating the feeding means, the drum and the air supplying means, and a single means for regulating the operation of the feeding means, the drum and the air supplying means to vary the rate of fuel consumption and the rate of supplying air to regulate the temperature of the fluid circulated about the radiator.

5. A heater construction comprising a gassing pot, means for continuously feeding solid fuel into the pot, a feeding and agitating drum in the pot for advancing the fuel through the pot while it is being consumed and for conducting the ash from the pot, means for supplying air to the bottom of the pot for combustion purposes, a supercombustion chamber, there being a restricted opening connecting the pot and said chamber, said supercombustion chamber having a tortuous passageway with baffles therein, a radiator surrounding the supercombustion chamber, said supercombustion chamber emptying into said radiator adjacent to the top thereof through one or more restricted outlets, a flue connected to the bottom of the radiator, means for conducting fluid to be heated about the radiator, power means for operating the feeding means and the drum, and a single means for regulating the operation of the feeding means and the drum to vary the rate of fuel consumption to regulate the temperature of the fluid circulated about the radiator.

6. A heater construction comprising a gassing pot, means for continuously feeding solid fuel into the pot, a feeding and agitating drum in the pot for advancing the fuel through the pot while it is being consumed and for conducting the ash from the pot, means for supplying air to the bottom of the pot for combustion purposes, a supercombustion chamber, there being a restricted opening connecting the pot and said chamber, said supercombustion chamber having a tortuous passageway with baffles therein, a radiator sur-

- rounding the supercombustion chamber, said supercombustion chamber emptying into said radiator through one or more restricted outlets, a flue connected to the radiator, means for conducting fluid to be heated about the radiator, power means for operating the feeding means and the drum, and a single means for regulating the operation of the feeding means and the drum to vary the rate of fuel consumption to regulate the temperature of the fluid circulated about the radiator. 80
7. A heater comprising, in combination, a gassing pot, means for continuously feeding a stream of solid fuel through said pot, a supercombustion chamber, there being a constricted outlet from the gassing pot into the supercombustion chamber, a radiator, said gassing pot delivering gases to the supercombustion chamber and the latter emptying into the radiator, said radiator enclosing the supercombustion chamber, and a flue connected to the radiator, an outlet for the gases from the supercombustion chamber and the inlet to the flue being at opposite sides of said supercombustion chamber so that the gases in the radiator circulate about the supercombustion chamber in passing to the flue. 85
8. A heater having, in combination, a gassing pot, means for continuously feeding solid fuel through the gassing pot, a supercombustion chamber provided by a refractory casing connected to the gassing pot by a restricted refractory walled opening and in which supercombustion chamber the smoke formed by the continuous feeding of fresh fuel into the gassing pot will be consumed, and means for conducting the gases delivered from said supercombustion chamber about the outside of said refractory casing to maintain such casing at a temperature at which said smoke will be ignited. 90
9. A heater having, in combination, a gassing pot, means for continuously feeding solid fuel through the gassing pot, a supercombustion chamber in communication with the gassing pot and formed by a refractory casing in which the smoke formed by the continuous feeding of fresh fuel into the gassing pot will be consumed, and means for conveying the gases delivered from the supercombustion chamber about the outside of said refractory casing to maintain said casing at a temperature at which said smoke will be consumed. 100
10. A heater having, in combination, a gassing pot, means for continuously feeding fresh solid fuel therein, means in the gassing pot for advancing the fuel in a stream through combustion zones in the pot and finally delivering the ash therefrom, a supercombustion chamber of refractory material in communication with the gassing pot for burning the smoke and gases liberated in the gassing pot, and means for conveying the gases from the supercombustion chamber about the outside thereof. 110
11. A heater having, in combination, a gassing pot, a radiator having an opening in an end thereof, a removable closure for the opening, and a casing providing a supercombustion chamber enclosed by the radiator, said casing being removably seated on the gassing pot and the bottom of the radiator to receive the gases from the pot and empty them into the radiator, said casing being removable through said opening in the radiator. 120
12. A heater comprising a gassing pot having a fuel feeding and agitating drum in the bottom thereof, means for supplying fuel onto the sur-
- face of the drum, common means for operating the fuel supplying means and for rotating the drum to feed the fuel through the pot and carrying the ash therefrom, and means for regulating the rate of supply of the fuel and the rate of rotation of the drum. 125
13. In a heater, a gassing pot, means for feeding a stream of coal to an inlet therein, a rotary drum in the pot for feeding the coal forwardly from the coal inlet, means for supplying air about the stream of coal, the inner surface of the wall of said pot opposite said inlet being at an inclination to deflect downwardly any ribbon of coal tending to bridge over to said wall, and a secondary rotary drum adjacent said wall for feeding coals approaching said wall back toward said first drum, the parts being so arranged that the air is flowable about said secondary drum and up along said wall. 130
14. In a heater, a gassing pot, means for feeding a stream of coal to an inlet therein, a rotary drum in the pot for feeding the coal forwardly from the coal inlet, means for supplying air about the stream of coal, the inner surface of the wall of said pot opposite said inlet being at an inclination to deflect downwardly any ribbon of coal tending to bridge over to said wall, and a secondary rotary drum adjacent said wall for feeding coals approaching said wall back toward said first drum. 135
15. In a heater, a gassing pot, means for feeding a stream of coal to an inlet therein, a rotary drum in the pot for feeding the coal forwardly from the coal inlet, means for supplying air about the stream of coal, and a secondary rotary drum adjacent the wall of the pot opposite said coal inlet for feeding coals approaching said wall back toward said first drum, the parts being so arranged that the air is flowable about said secondary drum and up along said wall. 140
16. In a heater, a gassing pot, means for feeding a stream of coal to an inlet therein, a rotary drum in the pot for feeding the coal forwardly from the coal inlet, means for supplying air about the stream of coal, and a secondary rotary drum adjacent the wall of the pot opposite said coal inlet for feeding coals approaching said wall back toward said first drum. 145
17. In a heater, a gassing pot, a secondary combustion chamber in communication with the gassing pot and adapted to provide a reservoir of heat for igniting unburned coal gases, means for conveying the gases of combustion from said secondary combustion chamber about the outside thereof, means for feeding coal to said gassing pot, means for positively feeding air to said gassing pot, said coal and air feeding means being synchronized to deliver the coal and air substantially in proper predetermined proportion to produce complete combustion, and means for varying the rate of the coal and air feed. 150
18. Apparatus of the class described, comprising means for feeding solid fuel in a stream, a gassing pot for receiving the fuel therefrom, means in the gassing pot for conducting the fuel therethrough while being consumed and for delivering the ash therefrom, means supplying air to the bottom of the gassing pot in excess of that required for combustion in the gassing pot, means for conducting the products of combustion, the excess air and the unburned gases from the gassing pot comprising a casing, there being a constriction between the gassing pot and casing, said casing defining a tortuous passageway, said gassing pot delivering the excess air to the casing to 155

be mixed with the gases in said passageway, and means for conveying the gases from the said passageway about said casing.

19. Apparatus of the class described, comprising means for feeding solid fuel in a stream, a gassing pot for receiving the fuel therefrom, means in the gassing pot for conducting the fuel therethrough while being consumed and for delivering the ash therefrom, means supplying air to the bottom of the gassing pot in excess of that required for combustion in the gassing pot, means for conducting the products of combustion and the unburned gases from the gassing pot comprising a casing, said casing defining a tortuous passageway, the gassing pot being adapted to deliver free heated air to be mixed with the gases in said passageway, and means for conveying the gases from said passageway about said casing.

20. Apparatus of the class described, comprising means for feeding solid fuel in a stream, a gassing pot for receiving the fuel therefrom, means in the gassing pot for conducting the fuel therethrough while being consumed, means supplying air to the bottom of the gassing pot in excess of that required for combustion in the gassing pot, means for conducting the products of combustion and the unburned gases from the gassing pot, said means comprising a casing defining a tortuous passageway, said gassing pot delivering free air to be mixed with the gases in said passageway, and means for conveying the gases from said passageway about said casing.

21. Apparatus of the class described, comprising means for feeding solid fuel in a stream, a gassing pot for receiving the fuel therefrom, means in the gassing pot for conducting the fuel therethrough while being consumed, means supplying air to the bottom of the gassing pot, means for conducting the products of combustion and the unburned gases from the gassing pot, said means comprising a casing defining a tortuous passageway, and means for conveying the gases from said passageway about said casing.

22. Apparatus of the class described, comprising means for feeding solid fuel in a stream, a gassing pot for receiving the fuel therefrom, means in the gassing pot for conducting the fuel therethrough while being consumed, means supplying air to the bottom of the gassing pot, means for conducting the products of combustion and the unburned gases from the gassing pot, said means comprising a casing defining a tortuous passageway of such length as to be adapted substantially to retard the flow of gases therethrough and thoroughly mix the same therein, and means for conveying the gases from said passageway about said casing.

23. In a heater, a radiator, a gassing pot, means for supplying coal in a stream through the pot and

means for supplying air thereto, said air being delivered to said gassing pot in excess of that required for combustion in said pot, means into which the gassing pot delivers the gases, burned and unburned, along with free air, said means providing a reservoir of heat and comprising a core through which the gases pass, said core being mounted in the radiator and delivering the gases of combustion thereto, an outlet from said core at one side of the core, and a flue connected to the radiator at another side of the core whereby the gases of combustion flow about the core to the flue.

24. In a heater, a gassing pot and a fuel feeding and agitating drum in the bottom portion of the pot by which the fuel is fed while burning, means for feeding a continuous stream of fuel from the rear onto the top of said drum and a grate in front of said drum and extending beneath the drum to a point at which the ash may be delivered from said gassing pot and providing a passage from the burning fuel between the drum and said grate whereby the stream of fuel is inverted in passing through said gassing pot, and means for supplying air about said stream of fuel.

25. A heater comprising, in combination, a foundation, an ash box provided therein, a rotary drum over said ash box, a gassing pot provided on said foundation, said drum being at the bottom of said pot, means for supplying solid fuel onto the drum, a casing of refractory material resting on said foundation providing a supercombustion chamber and defining a passageway leading from the pot, and a heat radiating casing resting upon the foundation and surrounding the refractory casing, said supercombustion chamber having an outlet to deliver the gases to said heat radiating casing, said heat radiating casing having an outlet for the gases in a wall of said heat radiating casing opposite said first named outlets whereby the gases delivered from the refractory casing pass about said refractory casing to the outlet in said heat radiating casing.

26. A heater having, in combination, a gassing pot, means for passing a stream of fresh solid fuel through the pot, a supercombustion chamber in communication with the gassing pot and defined by a casing of refractory material providing a tortuous passage for receiving the gases from the pot, a radiator in which said supercombustion chamber is mounted, said supercombustion chamber having an outlet emptying the gases into the radiator, and means on a side of said supercombustion chamber opposite to said outlet for conveying the gases from the radiator whereby the gases surround the supercombustion chamber.
